SHAVING BRUSH

Filed Feb. 10, 1928

Inventor
James Alex Denby Watt
By B. Singer, Atty

UNITED STATES PATENT OFFICE

JAMES ALEX DENBY WATT, OF LONDON, ENGLAND

SHAVING BRUSH

Application filed February 10, 1928, Serial No. 253,396, and in Great Britain March 16, 1927.

This invention relates to shaving brushes of the type comprising a hollow outer sleeve mounted to telescope on the bristle holding shank between stops on the shank, so that in 5 one extreme position of the parts the hollow sleeve comes around the shank leaving the bristles free for use, and in the other extreme position the sleeve surrounds and protects the bristles, and having a detachable foot for 10 the shank, which foot when removed from the shank also forms a cap to cover in the open end of the sleeve.

According to the present invention the detachable foot member is formed at one end 15 with a recess or projection to engage with a correspondingly shaped portion at the end of the shank and at the other end has another recessed portion adapted to engage with the upper end of the sleeve.

20 In order that the invention may be better understood, it will now be described with reference to the accompanying drawings in which:—

Fig. 1 is an exterior elevation of a preferred form of shaving brush constructed according to the invention in the position for use.

Fig. 2 is a sectional elevation with the parts in a similar position to that shewn in Fig. 1.

30 Figs. 3 and 4 are similar views to Figs. 1 and 2, with the sleeve member moved to surround the bristles, and

Figs. 5 and 6 are similar views to Figs. 1 and 2 with the sleeve moved to surround the 35 bristles and with the foot detached from the shank and functioning as a cap to close in the open end of the sleeve.

In the drawings, 7 is the shank of the brush, 40 which may be formed hollow with a closed lower end or may be formed solid as desired. The shank is provided on the exterior with a screw thread 8 and has mounted in any suitable manner in the upper end thereof the bristles 9. The lower end of the shank has 45 a reduced portion 10 and the portion of the shank coming adjacent the bristles is enlarged, the enlargement being shewn at 11.

50 12 is a sleeve adapted to fit over the shank 7 and provided at the lower end with one or two turns of a screw thread 13 adapted to en-

gage with the thread 8 on the shank 7. 14 is a member adapted to fulfill a dual capacity. This member at one end is formed with a recess 15 adapted to fit over and engage tightly with the reduced portion 10 of the shank. 55 At the other end this member is formed with a dome-like hollow interior 16, a partition 17 dividing the recess 15 and the dome portion 16. Beyond the dome 16 the member 14 is provided with an enlargement 18 adapted to 60 engage over the upper end of the sleeve 12. The member 14 is provided on the exterior with serrations 19 and the sleeve 12 is also formed with serrations 20.

To assemble the brush which comprises 65 three portions, that is to say the shank and bristles, the sleeve and the member 14, the reduced end 10 of the shank is passed into the open end of the sleeve 12 which comes remote from the threaded portion 13. When the 70 screwed end of the shank comes to the thread 13 the parts are rotated to bring the screw threaded portions 13 and 8 into engagement. Upon continued rotation the end of the shank 75 is projected through the screw threaded end of the sleeve 12. The member 14 can now be engaged with the reduced portion 10 as shewn in Figs. 1 to 4 and in this position the member 14 forms the foot for the brush. When the brush is in the position shewn in 80 Figs. 1 and 2 it can be used as an ordinary shaving brush and in these figures it will be seen that the bristles 9 project to the maximum extent.

By screwing the sleeve 12 with respect to the shank 7 it can be brought into the position shewn at Figs. 3 and 4 so that the sleeve 12 surrounds the bristles 9. In this position the member 14 can be removed from 85 the reduced portion 10 and the enlargement 18 engaged over the end of the sleeve 12 as shewn in Figs. 5 and 6. In this position it will be appreciated that the member 14 forms a cap to the sleeve 12 and entirely covers in 90 the bristles 9, the dome 16 accommodating the upper end of the bristles as shewn. The enlargement 11 coacts with an inwardly 95 projecting portion 21 in the sleeves 12 to limit the movement of the sleeve in the upward direction as shewn in Figs. 4 and 6. 100

Although the sleeve 12 and shank 7 have been shewn and described in screw threaded engagement, it is of course obvious that they may simply be in frictional engagement so that the sleeve can slide over the shank, or again the engagement may also include a pin and slot. In using the brush it is also possible where desired to have the sleeve 12 in any desired position intermediate the extreme positions of its movement with respect to the shank 7, so that the bristles 9 project from the sleeve only to an extent that may be desired.

Although the member 14 has been described as engaging with the reduced portion 10 by friction and as engaging by the enlargement 18 with the upper end of the sleeve 9, it is of course obvious that in place of these push-on frictional engaging actions, in some cases the engagement may be otherwise effected for instance the end of the shank 7 may be screw threaded and the member 14 correspondingly threaded to engage therewith, or either or both engaging surfaces may be knurled or tapered.

Similarly, the engagement between the member 14 and the sleeve 12 may be a screw threaded one. Further, in place of the member 14 engaging over the shank 7, in some cases the shank may have a recess into which a projecting portion on the member 14 engages by frictional, screw threaded or other fit.

The invention is not limited to the particular forms or details of construction described as these may be varied to suit particular cases, within the scope of the appended claim.

What I claim and desire to secure by Letters Patent of the United States of America is:—

A shaving brush comprising a shank, bristles carried by the shank, an outer sleeve mounted for longitudinal movement on the shank and arranged when in one position to surround and protect the bristles, said shank and sleeve being provided with coengaging screw threads and means to limit the extent of movement of the sleeve, and a foot member provided at one end of the recess to receive and closely fit on the outer end of the shank and thereby detachably secured to the shank, said foot member being provided at the opposite end with a recess to receive and closely fit on the outer end of the sleeve and with a chamber to enclose and protect the outer ends of the bristles.

In witness whereof I affix my signature.
JAMES ALEX DENBY WATT.
